UNITED STATES PATENT OFFICE.

ROYAL L. BOULTER, OF LOS ANGELES, CALIFORNIA.

TELEGRAPH-KEY.

1,178,291.

Specification of Letters Patent.

Patented Apr. 4, 1916.

Application filed August 1, 1914. Serial No. 854,562.

To all whom it may concern:

Be it known that I, ROYAL L. BOULTER, a citizen of the United States, residing at Los Angeles, county of Los Angeles, and State of California, have invented certain new and useful Improvements in Telegraph-Keys, of which the following is a specification.

This invention relates to telegraph keys.

10 The present invention relates to that class of telegraph keys known as "transmitters" or "vibrators" which employ a vibratory reed in connection with a key for the purpose of automatically making the dots of the Morse code, to thereby relieve the operator of the repeated finger and wrist movements necessary with the ordinary telegraph key.

20 My invention relates particularly to those transmitters employing a dot key or key lever which is disconnected from the vibratory reed and wherein the dash forming key lever is entirely separate from the dot forming key lever. Transmitters of the class to 25 which my invention belongs have their independent key levers arranged for lateral movement by the thumb and forefinger and are particularly designed for sending messages rapidly and with minimum effort on 30 the part of the operator and are useful to operators having writers' cramp or telegraphers' paralysis.

The present invention is an improvement 35 on the telegraph keys or transmitters set forth in my Patent No. 1,074,831, dated October 7, 1913, and application Serial No. 787,696, filed September 2, 1913.

40 Heretofore telegraph transmitters or vibrators have been provided as separate instruments from the old style of Morse key and designed to be placed on the desk or table beside the Morse key and thrown in circuit by a jack or plug inserted in between the contact lip and base frame of the 45 circuit closer of the Morse key. The constant use of the jack or plug has resulted in spreading the contact lip of the Morse key and in the course of time, the circuit is left entirely open at this point, and the contact 50 lip of the Morse key finally breaks off altogether.

One object of the present invention is the provision of a telegraph transmitter or vibrator which can be directly connected to 55 the old style of Morse key without requiring

a connecting jack or plug and cord, thereby obviating the defects previously specified and which are incident to the use of a jack or plug. In practice, I provide any suitable means for connecting the transmitter to the frame of the Morse key, in a detachable manner by preference, and any preferred means for effecting contact with the circuit closer strip of the Morse key at any point thereof. In the embodiment of the invention hereinafter described and which is shown in the accompanying drawings, clamps are provided to engage the trunnion screws of the key lever of the Morse key and a spring-actuated contact member is arranged on the transmitter so that it will bear upon the contact lip of the circuit closer of the Morse key. I wish it understood, however, that, believing myself to be the first to combine a transmitter or vibrator key with a Morse key, I do not limit myself to the manner in which the transmitter is included in circuit with the Morse key, and I lay claim to the generic invention involved in this combination of the vibrator 75 and Morse key. Furthermore, I do not limit the invention in this respect to the use of a vibrator or transmitter key employing the particular improvements which are herein-after described, as I am well aware that 80 other transmitters or vibrators can be combined with Morse keys in carrying out this 85 branch of my invention.

By eliminating the plug or jack and the spreading of the contact lip of the Morse 90 key, the present invention cures a serious defect met with in practice in the connection and use of a transmitter with a Morse key.

A further object of the present invention is the provision of an improved telegraph 95 transmitter or vibrator, regardless of whether or not such vibrator is provided with means whereby it may be directly applied to a Morse key as previously set forth. The present improvements, in that respect, 100 relate more particularly, first, to the vibratory reed; contact mechanism therefor; secondly, to the spring retraction of the reed by direct spring tension exerted thereon; and third, to the provision of a dot key 105 lever which is pivotally mounted entirely independently of, and disconnected from, the vibratory reed and has adjustable means whereby the coöperation of said dot key lever with the vibratory reed may be 110.

changed at will. Those transmitters heretofore known to the art wherein the dot key lever has been mounted for movement separate from the vibrator or reed, have been themselves spring-actuated and have exerted a constraining or restraining action on the vibratory reed so that the reed was retracted by the interposition of the dot key lever between the spring mechanism and the reed, or, the reed has been directly connected to and carried by the dot key lever. In both of these types, there has been no provision for the direct retraction of the vibratory reed by spring means directly applied thereto and no adjustment of any kind has been provided to regulate the play of the dot key lever in reference to the reed.

One of the objects of the present invention is the provision of a vibratory reed which has its own spring-retracting means, and a dot key lever which is mounted independently of the reed and has adjustable means whereby its coöperation with the reed may be regulated to suit the characteristics of the operator.

Another object is to provide a novel adjustable double contact for the vibratory reed, whereby, when a series of dots are to be made, one set of contacts completes the circuit and another set automatically opens and closes it by the vibrations of the reed, but when only a single dot is to be made the temporary arrest of the reed by the first set of contacts will not set the reed into vibration. Consequently, in making a single dot, the reed and the automatic dot making means will move as an entirety, whereas when the dot key lever is held, after being actuated, a plurality of dots will be made until the key lever is released.

The transmitter of the present invention embodies the principle of the tapping contact mechanism of my patent and application hereinbefore referred to, but the improvements provide for a more delicate adjustment and tend to minimize the involuntary formation of what operators term "split" dots particularly in letters of the alphabet having but one dot such as "A" and "N". The present invention is adapted for both fast and slow work and for use on both long and short lines. By dispensing with the base which has heretofore been provided for transmitters, the present vibrator is more simple, compact and lighter than transmitters heretofore known to the art.

I have shown and described an embodiment of the invention adapted to carry out all of the objects hereinbefore recited, but I do not limit myself to the specific features, constructions, and combinations appearing therein as they are susceptible of modification in various ways, and the disclosure of the invention is to be considered as illus-

trative, rather than restrictive, of the scope of the invention.

In the accompanying drawings: Figure 1 is a side elevation showing the transmitter applied to an ordinary Morse telegraph key; Fig. 2, a section on line 2—2, Fig. 1, showing the manner in which the clamps attach the transmitter to the trunnion screws of the Morse key; Fig. 3, a side elevation of an old style Morse key such as appears in Fig. 1; Fig. 4, a side elevation, taken opposite to that of Fig. 1, showing the transmitter disconnected from the Morse key; Fig. 5, a plan view of the instrument when separate from the Morse key; Fig. 6, a front elevation showing the dot and dash key levers broken off; Fig. 7, a detail perspective of the vibratory reed and contact mechanism, the bob being omitted; Fig. 8, a detail perspective looking toward the other side of the vibratory reed; Fig. 9, a detail perspective of the rear end of the dot key lever, the adjusting screw being omitted; Fig. 10, a similar view of the dash key lever, parts of Figs. 8, 9 and 10 being in separated, but associated relation to illustrate the positions of these parts when in operative relation; Fig. 11, a horizontal detail view partly broken away, illustrating the relative positions of the vibratory reed, dot lever, dash key lever and the adjustable connection for the reed contact bar; Fig. 12, a detail cross section showing the insulated adjustable joint for the vibrator contact; Fig. 13, a detail perspective, broken away, showing the spring-actuated contact of the transmitter and the manner in which it bears upon the contact lip of the Morse key when the transmitter is combined therewith; and Fig. 14, a bottom detail plan view showing certain electrical connections.

In Figs. 1, 2 and 3, there is illustrated a well known type of Morse key which is in common use in telegraph offices. Heretofore vibrator or transmitter keys have been provided with their own base and provided with a jack or plug included in circuit with the dot and dash mechanism thereof. This plug or jack has been inserted underneath the contact lip 1 (Figs. 1, 3 and 13) of the old style key, thus obviating the necessity of any operation of the key lever 2 of the old instrument. The circuit closer of the old instrument is shown at 3. The action of the plug or jack is a wedging action and in a relatively short time the contact lip or member 1 is bent up, by repeated insertions of the jack or plug beneath said lip so that eventually the jack or plug of the transmitter does not make contact with said lip and, consequently, the circuit is left open, or, the lip is pried up so far that when the circuit closer 3 is closed, after withdrawing the jack or plug, the circuit including the Morse key is left open without the operator

knowing it. The most serious objection to the use of these plugs or jacks for connecting semi-automatic transmitters is that the repeated wedging of the plug eventually breaks the lip 1 completely off, which necessitates loss of time in removing the Morse key and substituting another or substituting another contact strip. With my transmitter or vibrator, there is used no jack or plug of any character, the instrument being directly connected to the Morse key, as shown in Figs. 1 and 2. Any suitable means may be provided to carry out this end, the invention consisting broadly in the direct attachment of the transmitter to the Morse key and in the use of a connection which will permit ready detachment of the transmitter from said key. My transmitter is provided with a metallic base 4 which has legs 5 preferably provided with feet 6 of insulating material, said feet being adapted to rest directly on the table or desk which is indicated by the line 7. To the plate 4 is secured by screws or in any other manner, a bar 8 which carries clamp blocks 9 having openings or notches 10 to receive the trunnion screws 11 of the Morse instrument, and there are provided clamping screws 12 for securing the clamps to the trunnion screws, as shown in Figs. 1 and 2. Connected to, but insulated from the plate 4, at 13, is a contact 14 (Fig. 13) consisting of a tube containing a spring 15 which bears upon a bifurcated contact member 16 which straddles a pin 17 carried by the tube 14. The play of the plug 16 is sufficient to cause it to adapt itself to the contact lip 1 of any of the usual types of Morse instruments, one of which is shown in Figs. 1, 2 and 3. When the transmitter is superposed on the Morse key, as shown in Fig. 1, and the clamps are secured to the trunnion screws 11, the contact plug 16 then bears upon the lip 1. The part of the circuit including the frame of the Morse instrument, then includes the frame 4 of the transmitter and the remaining part of the circuit is completed through the insulated tube 14 and plug 16 and the contact lip 1. This leaves the contact lip 1 free to be closed by the circuit closer 3 in the usual manner, and I am, therefore, enabled to dispense with a separate circuit closer on the transmitter. As shown in Fig. 14, the tube 14 and plug 16 are connected by a metal strip 18 to the screw 19 that secures the dash contact pillar 20 to the plate 4. Insulation 21 prevents electrical contact between the pillar 20 and the plate 4.

Referring to Fig. 5, there is carried by the pillar 20 the adjustable dash contact 22 with which the dash lever 23 co-operates through its contact 24. The dash lever is provided with its own finger or key 25 and is pivoted by its trunnion 26 to the bar 27 at its upper end, and its lower end receives

the conical tip of an adjustable screw 28. An adjustable stop 29 (Figs. 6 and 10) is carried by the dash key lever 23 and is adapted to engage the cross bar 27 to limit the retraction of the dash key lever by the spring 30 (Figs. 5 and 6), said spring being adapted for adjustment by a screw 31, which passes through a plate 32 (Figs. 1, 5 and 6) secured to the bar 27. The dash lever is adapted to be operated independently of the dot lever, for the formation of the dashes and it is mounted independently of the dot lever, as clearly shown in Figs. 5, 9 and 10.

Referring to Fig. 14, a metal strip 33 extends from the screw 19 to a screw 34 which secures a pillar 35 of the main dot contact to the plate 4. The pillar 35 is insulated from the plate 4, as shown at 36, Fig. 4, and it carries an adjustable main contact 37, Fig. 5. It is through the contact 37 that the circuit is initially closed when the dot key lever is operated either to form a single dot or to form a plurality of dots.

Referring now to Figs. 5, 6 and 11, the vibratory reed 38 which is of resilient material throughout, is connected to plates 39, preferably by riveting, and these plates have a trunnion 40 whose upper tip is journaled in a screw 41 (Figs. 1 and 6), while its lower end or point is received in a concavity in the cross bar 27, whereby the vibratory reed is pivotally mounted. Other means for pivotally mounting the said reed may be employed. The vibratory reed is directly and positively spring-retracted by a compression coil spring 42 (Figs. 5, 6 and 11) which engages the front end thereof, the latter being provided with an aperture 43 (Figs. 7 and 8) to receive one tip of the said spring, while the other tip thereof is entered in the hollow end of an adjusting screw 44 which is threaded through the bracket 32. By this means, the retracting tension of the spring on the reed may be changed at will. It will be seen, therefore, that the vibratory reed is normally retracted to the position shown in Fig. 5 solely by the action of said spring, as in my instrument the dot key lever is mounted entirely separate from the reed and exerts no retracting function on said reed, nor is it directly connected to the reed.

Referring again to Figs. 7 and 8, secured between the plates 39 is a tapping spring 45 which is resilient throughout its length and projects freely from between said plates and lies in an open portion 46 of the reed. The free end of this tapping spring is provided with a stop or arrester 47 which overlaps the reed and is adapted to bear against it, due to the resiliency of the said spring 45. Spring 45 is provided with a contact 48 (Figs. 5 and 7) adapted to co-operate with the tip 49 of an adjustable contact screw 50 for the purpose of automatically forming a plurality of dots. The screw 50 is carried by a rod or

4
tube 51 which is slidably mounted in a block 52 (Fig. 11) so that the said rod or tube 51 can be moved lengthwise in relation to the length of the reed 38. Consequently, a very fine relative adjustment of the contacts 48, 49 can be effected. The block 52 carries a contact 53 adapted to engage the contact 37 when the vibrator is swung against the retracting tendency of the spring 42.

10 Referring to Figs. 11 and 12, the plates 39 are provided with apertures in which is a bushing 54 of insulating material, through which passes the screw-threaded stem 55 which has a head 56 provided with a hole of 15 approximately the same size as the hole in block 52 which receives rod or tube 51, and the rod or tube 51 passes through the said hole. A shoulder 57 is provided to bear against the inner side of the block 52. The 20 lateral pull exerted firmly clamps the rod or tube 51 to the block 52 when the parts are tight. Insulating washers 58 and a nut 59 on the screw 55 complete the means for clamping the parts together so that the block 52 and the rod or tube 51 will be firmly secured 25 in relation to the reed 38. It will be observed, however, that the block 52 is pivotally mounted on the part 56, and consequently, the contacts 49 and 53 can be raised or lowered 30 in relation to contacts 48 and 37, respectively, whereby up and down adjustment, in addition to longitudinal adjustment heretofore referred to, is obtainable. A very fine adjustment of the contact mechanism is, 35 therefore, insured.

When the vibratory reed 38 is moved in opposition to the tendency of the compression spring 42, the contacts 37 and 53 are brought together. If but a single dot is to 40 be made, the reed will be at once released by the operator, but if a plurality of dots are desired, the operator retains the engagement of the contacts 53 and 37 and the arrest of the reed 38 thereby sets it into vibration, 45 whereupon it repeatedly separates from and strikes the stop or arrester 47 by alternate movements and thus exerts a tapping action on said arrester 47, which is in turn communicated to the flexible member 45, resulting 50 in the contact 48 alternately repeatedly striking and disengaging from the contact 49, whereby a plurality of dots are formed. During this vibration of the reed 38, the contacts 53 and 37 remain engaged. If the reed 55 38 is swung quickly and then released, only one contact will be made, that at 37, 53, and the contacts 48 and 49 will not separate. A single dot will thus be formed. The reed is provided with an elongated slot 60 to permit 60 adjustment of the bob or weight 61. By shifting the bob or weight 61 to different positions, the rapidity of vibration of the reed may be increased or diminished. A loosely mounted stop 62 carried by pillars 65 63 arising from base 4, constitutes an arrest-

ing means for preventing vibration of the reed when it is released and retracted by the compression spring 42.

Heretofore vibratory reeds of transmitters have either been directly carried by the dot lever and bodily movable therewith, or, such reeds have been constrained or restrained by the dot lever and spring means employed to hold the dot lever in contact with the reed or to transmit motion from the dot lever to the reed.

I have improved on these prior constructions by mounting the dot lever 64 entirely separate from the reed and also from the dash lever 23, as will be clear from Figs. 5, 9, 10 and 11. The dot lever 64 has a trunnion 65 which at its upper pointed end 66 is pivotally received in an opening in the lower face of bar 27, its lower end having a concavity which receives the tip of an adjustable screw 67 carried by plate 4, as shown in Fig. 6. Secured to and rising from the dot lever 64 at the rear end thereof is a stud 68, and located forwardly of the trunnion 65 is another stud 69. The stud 68 is adapted to engage one of the plates 39 when the finger-piece 70 of the dot lever 64 is moved toward the finger-piece 25 of the dash lever. The movement being of an amplitude determined by the adjustment of a set screw 71 (Figs. 5 and 11), whose stem is adjustably threaded through the opening 72 in the stud 69, Fig. 9. The tip of the screw 71 is adapted to engage the plate 39. The dot lever 64 is idly mounted. The movement of the finger-piece 70 away from the finger-piece 25 is determined by the distance the tip of the screw 71 is from the plate 39. The effective action of the dot lever in moving the reed from the position shown in Fig. 5 and against the retracting action of the spring 42 is determined by the distance the stud 68 moves before it engages the plate 39. Adjustment is, therefore, provided through the screw 71, as clearly shown in Fig. 11, for any desired amplitude of movement of the dot lever 64 before the stud 68 effectively engages the reed to move it, and consequently, adjustments may be had to accommodate the peculiarities of finger and wrist movements of any operator who may use the instrument. So far as I am aware, I am the first to provide a dot key lever which has neither a constraining nor restraining action on the reed and is used only for positively actuating the reed and is also adapted for adjustment in relation to the reed.

In using the instrument, pressure on the finger-piece 25 in opposition to the spring 30, will cause the contacts 24 and 22 to be brought together for the formation of dashes. The forefinger is used for this operation. The thumb is employed to swing the finger-piece 70 toward finger-piece 25

for the formation of one or more dots. A quick movement and release of the finger-piece 70 merely brings the contacts 37 and 53 together for the formation of a single dot. There is then no break and make at the contacts 48, 49. If, however, the pressure is retained on the finger-piece 70, the contacts 37 and 53 remain in engagement and the reed 38 vibrates, causing separation 10 and engagement of the contacts 48, 49, as previously explained, thus automatically forming a plurality of dots which operation continues, within certain limits, as long as the pressure is retained on the finger-piece 15 70, but immediately the pressure is released, the compression spring 42 moves the reed back to normal position and the bob 61 then strikes the stop 62, which stops the reed from vibrating. The circuit is then broken 20 both at 37, 53 and 48, 49.

Having thus described my invention, what I claim as new and desire to secure by Letters Patent, is:—

1. The combination with a main telegraph key having a freely projecting contact lip and a circuit closer adapted to engage said lip, of a second telegraph key having means to engage the frame of the key first-named and also provided with a spring-actuated 25 electrical contact adapted to frictionally engage the contact lip aforesaid.

2. The combination with a telegraph key of the "Morse" type, of a telegraph key of the transmitter or vibrator type, screw 35 clamps carried by the last-named key which are adapted to engage the trunnion or pivot nuts or heads of the "Morse" key, and a contact carried by the transmitter key adapted to engage the circuit closing contact of the 40 "Morse" key, the transmitter key being adapted to be positioned in superposed relation to the "Morse" key.

3. In a telegraph key, the combination with a spring-retracted vibratory reed, and 45 contact means coöperatively related thereto for the formation of dots, of an independently and idly mounted pivoted dot key lever having means on one side of its pivotal point adapted to engage the reed, and carrying 50 adjustable means on the opposite side of its pivotal point for regulating the idle play of the key lever in relation to the vibratory reed.

4. In a telegraph key, the combination 55 with a spring-retracted vibratory reed, and contact means coöperatively related thereto for the formation of dots, of an independently and idly mounted dot key lever adapted to engage the reed, and an adjustable 60 screw carried by the key lever and adapted to coöperate with the reed for the purpose of regulating the idle play of the lever in relation to the reed.

5. In a telegraph key, the combination 65 with a pivotally mounted vibratory reed, of

a spring directly acting thereon adapted to normally retract the reed, contact means with which the reed is adapted to coöperate when moved in opposition to the retracting tendency of the spring aforesaid, and a key 70 lever pivoted independently of the reed and having means on opposite sides of its pivotal point adapted to engage the reed.

6. In a telegraph key, the combination with a pivotally mounted vibratory reed, 75 of a spring coöperating therewith adapted to retract the reed, contact means engaged by the reed when said reed is moved in opposition to the retracting tendency of the spring, and a key lever pivoted independently of the reed and movable independently thereof, said lever having studs arranged on opposite sides of the pivotal point of the reed and adapted to coöperate therewith. 80

7. In a telegraph key, the combination with a pivotally mounted vibratory reed, 85 of a spring coöperating therewith adapted to retract the reed, contact means engaged by the reed when said reed is moved in opposition to the retracting tendency of the spring, a key lever pivoted independently of the reed and movable independently thereof, said lever having studs arranged on opposite sides of the pivotal 90 point of the reed and adapted to coöperate therewith, and an adjustable screw carried by one of said studs and controlling the engagement of the studs with the reed.

8. In a telegraph key, the combination 95 with a vibrator, of a leaf or ribbon spring connected to and movable with the vibrator, whereby said vibrator and leaf or ribbon spring are adapted to move together as an entirety, said vibrator, and leaf or ribbon spring being coöperatively related so that the vibrator will deliver taps upon the leaf or ribbon spring, contacts respectively carried by the ribbon spring and vibrator adapted to be opened and closed by the 100 action of said leaf or ribbon spring, and a key lever adapted for swinging the vibrator.

9. In a telegraph key, the combination 115 with a vibrator, of a leaf or ribbon spring connected to and movable with the vibrator, whereby said vibrator and leaf or ribbon spring are adapted to move together as an entirety, said vibrator and leaf or ribbon spring being coöperatively related so that the vibrator will deliver taps upon the leaf or ribbon spring, contacts adapted to be 120 opened and closed by said leaf or ribbon spring, spring means directly coöperating with the vibrator and adapted to retract it, and an independently mounted key lever 125 adapted to coöperate with the vibrator to move it in opposition to the retracting tendency of said spring.

10. In a telegraph key, the combination 130

- with a vibratory pivotally mounted reed, of a leaf or ribbon spring carried thereby and bodily movable therewith which is arranged and adapted in relation to the reed 5 so that the said reed will deliver taps thereon, a contact carried by and insulated from said vibratory reed, said contact being adapted to be engaged by the leaf or ribbon spring aforesaid and to be opened and 10 closed by the tapping action of the vibrator on said leaf or ribbon spring, a main contact which is closed when the vibrator is moved from normal position, and means for operating said vibrator.
- 15 11. In a telegraph key, the combination with a vibratory pivotally mounted reed, of a leaf or ribbon spring carried thereby and bodily movable therewith which is arranged and adapted in relation to the reed 20 so that the said reed will deliver taps thereon, a contact carried by and insulated from said vibratory reed, said contact being adapted to be engaged by the leaf or ribbon spring aforesaid and to be opened and 25 closed by the tapping action of the vibrator on said leaf or ribbon spring, a main contact which is closed when the vibrator is moved from normal position, and an independently mounted key lever having an 30 idle motion in relation to said vibrator and adapted to operate the vibrator in opposition to the retracting tendency of the spring aforesaid.
12. In a telegraph key, the combination 35 with a vibrator, of a contact carried thereby, another contact carried by and insulated from the vibrator, and a main or primary contact extraneous to the vibrator and adapted to be closed when the vibrator is 40 moved to thereby complete the circuit and

also act as a stop to arrest the vibrator so that said vibrator will be set in vibration.

13. In a telegraph key, the combination with a vibrator, of a contact carried thereby, another contact adjustably mounted on the 45 vibrator and adapted to coöperate with the contact aforesaid, the last-named contact being insulated from the vibrator, and a combined stop and contact extraneous to the vibrator and adapted to complete the 50 circuit through the insulated contact aforesaid.

14. In a telegraph key, the combination with a vibrator, and a contact carried thereby, of a contact adapted to coöperate with 55 the vibrator, said contact being mounted upon and insulated from the vibrator and having a slideable and rockable connection therewith, and a combined stop and contact extraneous to the vibrator and adapted to 60 engage the contact last named.

15. The combination with a vibrator, of a contact carried thereby and coöperatively related thereto so that when the vibrator is vibrating it will deliver taps on said 65 contact, a rod or stem slideably and rockably carried by and insulated from the vibrator, a contact carried by said stem which is adapted to coöperate with the contact aforesaid, and a combined stop and contact 70 extraneous to the vibrator which is adapted to complete the circuit through said stem and contacts first-named.

In testimony whereof, I hereunto affix my signature in presence of two witnesses.

ROYAL L. BOULTER.
